INCLOSED-FUSE ELEMENT.

1,213,777.

Specification of Letters Patent. Patented Jan. 23, 1917.

Application filed May 8, 1916. Serial No. 96,026.

To all whom it may concern:

Be it known that I, EDWARD E. ROBERTS, a citizen of the United States, residing at Hartford, in the county of Hartford and State of Connecticut, have invented a new and useful Improvement in Inclosed-Fuse Elements, of which the following is a specification.

It is a common expedient to make the fusible elements of certain classes of inclosed electric fuses of a number of very thin zinc ribbons. For instance, a 2,500 volt fuse may have a number, (depending on the ampere capacity), of ribbons approximately six inches long, .15 inches wide, and .0025 inches thick. These ribbons are extremely delicate and their ends must be attached to substantial interior conducting terminals which are secured, usually by solder, to the exterior terminals or blades by which the fuse is connected in the circuit with which it is to be used. In the manufacture of such fuses it is necessary to make up the fusible element as an integral structure before it is placed in its casing and the granular condensing material filled in about it. In order to connect the interior terminals and form a support therefor it has been customary to join them by a centrally arranged rod, and as this rod must be small yet rigid and must have high electrical resistance and considerable dielectric strength, a glass rod is usually employed for this purpose. This rod, however, being centrally located and surrounded by the ribbons, when the fuse is in use with a current somewhat near its rated capacity, is subjected to considerable heat, and being of glass this heat causes it to expand quite a little. The casings of these fuses are usually formed of fiber which when heated has a tendency to dry out and shrink, and the shrinkage of the casings and the expansion of the glass supporting rod being opposite in effect, sometimes subjects the parts to considerable stress. In fact the expansion of the glass rod has frequently torn apart the fusible ribbons and has broken the soldered connections between the interior terminals and the fuse blades. When the structure is made sufficiently strong to withstand the destructive effect of such expansion the small glass rod is liable to be fractured.

The object of the present invention is to so construct the fusible element of an inclosed electric fuse that the interior termi-

nals will be rigidly enough supported to permit quick handling in the process of manufacture, and yet sufficiently elastic so that if the tube shrinks the glass is not fractured, or if the glass expands and increases in length the ribbons are not disrupted and the soldered connections between the element terminals and the fuse blades not broken. In attaining this object the interior conducting terminals to which the fusible ribbons are secured and which are soldered to the fuse blades, are yieldingly connected by a non-conducting rod, preferably by cementing one end of a glass rod in a socket in one terminal and loosely inserting the other end of the glass rod in a socket in the other terminal against a spiral spring located in said socket. This spring tends to thrust the parts away from each other and keep the fusible ribbons tight, and yet will contract so as to permit shrinkage of the casing or expansion of the rod and thus eliminate all danger of rupturing the ribbons, breaking the terminal connections, or fracturing the glass.

Figure 1 of the accompanying drawings shows a side view of a fuse embodying this invention, with one end of the casing cut open to show the interior. Fig. 2 shows a side view of the fusible element. Fig. 3 shows a longitudinal section of one end of the element. Fig. 4 shows a longitudinal section of the other end of the element. Fig. 5 shows a transverse section of the element.

In the form of fuse illustrated the glass supporting rod 1 has one end cemented in a socket in the terminal 2 and its other end extending loosely into a socket in the terminal 3. A spiral spring 4 is placed in the socket in the terminal 3 so as to thrust between the bottom wall thereof and the end of the glass supporting rod. The terminals of the form of fuse shown have radiating lugs 5 to which the ends of the thin zinc ribbons 6 are secured. There may be any number of these ribbons, depending upon the desired capacity of the element. The terminals also have projecting ends 7 which are soldered to the blades 8. It is preferred to place small felt washers 9 on the rod close to the terminal 3 so as to prevent the entrance of any of the filling material into the spring socket. This element is placed in a casing 10 which is commonly made of a section of fiber tube.

On the ends of the tubular casing are placed the ferrules or caps 11 to which the blades are secured. These caps are usually perforated for the escape of air and gas when the 5 fuse blows, and inside of the caps are washers 12 of loosely woven fiber which prevent the filling material from sifting out through the vents in the caps, but permit the out flow of air and gas. The granular non-conducting and condensing medium 13 is, 10 of course, filled into the casing after the fusible element has been located therein, but before the cap at one end is applied.

With this construction the supporting rod 15 may be made of glass which is of high electrical resistance, has considerable dielectric strength and is rigid and sufficiently strong to withstand all ordinary strains, both electric and mechanical to which it is 20 subjected. This glass rod, when arranged in the manner described, supports the terminals and yet it is free to expand and the casing is free to contract without rupturing the delicate ribbons or causing the soldered joints between the terminals and the blades 25 to break.

The invention claimed is:

1. A fuse element comprising conducting terminals, a non-conducting supporting rod 30 extending from one terminal to the other,

cushioning means between one end of the rod and one terminal, and metallic ribbons connecting said terminals.

2. A fuse element comprising metallic terminals, a glass supporting rod extending 35 from one terminal to the other, cushioning means interposed between said rod and one terminal, and metallic ribbons connecting the terminals.

3. A fuse element comprising metallic 40 terminals, a glass supporting rod with its ends extending into sockets in said terminals, a spring arranged in the socket of one terminal and 45 thrusting against the end of said rod, and metallic ribbons connecting said terminals.

4. A fuse element comprising metallic terminals, a glass rod with its ends extending 50 into sockets in said terminals, a spring arranged in the socket of one terminal and 55 thrusting against one end of said rod, washers on said rod and closing the socket in the terminal containing said spring, and metallic ribbons connecting said terminals.

5. A fuse element comprising conducting terminals, a non-conducting supporting rod extending from one terminal to the other, and yieldingly connected therewith, and fusible conductors joining said terminals.

EDWARD E. ROBERTS.
